(57) **CLAIM**

The ornamental design for a personal mobility device, as
shown and described.

DESCRIPTION

FIG. 1 is a perspective view of a personal mobility device;
FIG. 2 is a front view thereof;
FIG. 3 is a back view thereof;
FIG. 4 is a left side view thereof;
FIG. 5 is a right side view thereof;
FIG. 6 is a top view thereof; and,
FIG. 7 is a bottom view thereof.

The broken lines are included for the purpose of illustrating
environmental elements only and form no part of the claimed
design.
